ILIA SEMOTIUK, OF VEGREVILLE, ALBERTA, CANADA, ASSIGNOR OF ONE-SIXTH TO
FEDOR WAKALIUK, OF VEGREVILLE, ALBERTA, CANADA.

ANTIBALKING DEVICE.

1,253,733.

Specification of Letters Patent. Patented Jan. 15, 1918.

Application filed May 7, 1917. Serial No. 167,078.

To all whom it may concern:

Be it known that I, ILIA SEMOTIUK, a subject of the King of England, residing at Vegreville, in the Province of Alberta and 5 Dominion of Canada, have invented certain new and useful Improvements in Anti-Balking Devices, of which the following is a specification.

This invention relates to devices for controlling animals and especially to an anti-balking device.

It is a well known and recognized fact that of all draft animals the mule is the most stubborn and is at all times inclined 15 to balk. Moreover, experience has taught that when a mule is seized with the desire to balk it is practically impossible with the existing means to cause him to move forward.

20 One important object of the invention is to provide a simple and efficient apparatus which may be used with balky mules and which, when in use, will so distract the mule's attention that it will produce a practically instantaneous cure for the attack of balking.

It is also well known that at times, when the balking fit is not too strong, the application of a whip or other irritating means 30 is effective. At other times it is found that the mule's attention will be distracted from his balking attack by tickling, as for instance by folding his ear down over a large and vigorous fly.

35 A second important object of the present invention is to provide an element for use in a balking device which shall combine in itself both an irritating and tickling effect so as to more effectually distract the attention of the mule from his stubborn fit.

40 With the above and other objects in view, as will be hereinafter apparent the invention consists in general of certain novel details of construction and combinations of 45 parts hereinafter fully described, illustrated in the accompanying drawing, and specifically claimed.

50 In the accompanying drawing, like characters of reference indicate like parts in the several views, and:

Figure 1 is a plan view of a portion of a pair of vehicle shafts showing the device applied thereto.

55 Fig. 2 is a section through such a pair of shafts showing the device in elevation.

Fig. 3 is a section on the line 3—3 of Fig. 2.

Fig. 4 is a section on the line 4—4 of Fig. 1.

Fig. 5 is an enlarged detail view of a portion of the irritating and tickling element used herewith.

In carrying out the objects of this invention there is provided on each of the shafts 10 adjacent the rear end thereof an upwardly and inwardly extending arm 11 which is bolted securely to the respective shaft and is provided on its upper end with a pivot pin or shaft 12 vertically arranged and carrying a wheel 13 having a grooved periphery. This wheel is preferably hollow and the rim of the wheel is connected to the pin 12, which is non-rotatable, by a spiral spring 14 so that the wheel is arranged exactly as the balance wheel of a watch only 75 on a much larger scale, the wheel thus constituting a balance wheel. Carried on each arm 11 and partially surrounding the respective wheel 13 is a guide channel 15 terminating in a guide funnel 16. Extending 80 from the grooved periphery of each of the wheels is a series of spurs 17 and passing through the guides 16 and engaged by the spurs 17 is a flexible irritating and tickling element in the form of a rope having a body 85 18 of horsehair wherein is laid up a multiplicity of hog bristles 19 which extend substantially radially from the body. One end of this horsehair rope may be allowed to extend backward toward the driver of the 90 vehicle to form an operating handle while the other end may be permanently connected to its balance wheel. Now, it will be obvious that if the loose end of the rope be grasped and pulled the springs 14 will 95 be brought into tension, thereby winding them up further or by partially unwinding them so that if the projecting end of the rope be loosened to let the apparatus run freely the wheels 13 will oscillate which will 100 cause reciprocation of the rope 18.

Now it is well known by all students of natural history that a mule's skin has little sensibility especially where covered with hair as on most parts of the animal. It is 105 also well known that the underside of a mule's tail at the part adjacent the body is without hair and I therefore preferably run the rope beneath the mule's tail as shown in Fig. 1 where the reciprocation under 110

the influence of the balance wheel will so produce an irritating and tickling effect as to distract the attention of the mule and cause him at once to move forward.

5 There has thus been provided a simple and efficient device of the kind described and for the purpose specified.

It is obvious that many minor changes may be made in the form and construction 10 of the invention without departing from the material principles thereof. It is not therefore desired to confine the invention to the exact form herein shown and described but it is wished to include all such as properly 15 come within the scope claimed.

Having thus described the invention, what is claimed as new, is:—

1. In a mule starter, a pair of oscillatory balance wheels positioned in spaced relation to lie on opposite sides of a mule, and a flexible irritating and tickling member 20 having its end portion connected to one of said balance wheels and arranged to en-

gage the other wheel and adapted to be brought into contact with a mule positioned 25 between said wheels.

2. The combination with a pair of vehicle shafts; of arms projecting upward from said shafts adjacent the rear end thereof, balance wheels carried by the upper ends of 30 said arms, guides partly surrounding said balance wheels, spurs on the rims of said wheels, and a rope extending through said guides and engaged by said spurs, one end of the rope projecting freely beyond its 35 guide.

3. In a mule starter, an irritating and tickling element consisting of a horse hair rope having hog bristles radiating therefrom. 40

In testimony whereof I affix my signature.

ILIA SEMOTIUK.
